UNITED STATES PATENT OFFICE.

ADRIANNA STÜRCKE, OF OSSINING, NEW YORK.

LAUNDRY BLUING.

1,219,186.

Specification of Letters Patent. Patented Mar. 13, 1917.

No Drawing.

Application filed June 13, 1913. Serial No. 773,520.

To all whom it may concern:

Be it known that I, ADRIANNA STÜRCKE, a citizen of the United States, residing in Ossining, in the county of Westchester and 5 State of New York, have invented certain new and useful Improvements in Laundry Bluing, of which the following is a specification.

This invention relates to laundry bluing, 10 and aims to provide certain improvements therein. Various bluings in powdered or solid form are now in commercial use, but these so far as I am aware are open to the objection that they are only partly soluble, 15 especially in cold water, and hence stain or discolor the fabrics. Various substances enter into their composition which are deleterious to the clothing, which substances finally load the fabric and cause it to crack 20 or otherwise injure it. Furthermore, if the clothing is left in such bluing solutions it speedily becomes sour and discolored.

According to the present invention I provide a bluing in powdered form which is 25 practically instantly soluble in water, either hot or cold, which will not discolor the clothing since there is no precipitate or insoluble sediment, and in which there is no danger of souring even if the clothes are permitted 30 to soak in the bluing solution for an indefinite period.

In proceeding to produce the bluing provided by my invention I take commercially pure borax, and pulverize the same finely, 35 passing it through a screen or screens until the desired fineness is obtained. I next take commercial "style P" in the trade, *i. e.*, soluble Prussian blue, ferric potassium ferrocyanid. This I also grind to a very fine 40 powder. I then mix the two thoroughly, preferably in the proportion of about 95 per cent. borax to five per cent. of blue. In the mixing operation I preferably sift the finely divided borax into the powdered commercial blue, preferably stirring or shaking 45 during the process of admixture so that an even and thoroughly mixed product is obtained. The bluing is then ready for use, and should be added to the water by sifting

it in through a sieve-topped can or otherwise. 50

Soluble Prussian blue is known as "style P" and is used to some extent in large laundries. In such uses, however, it requires special preparation because of the difficulty 55 in dissolving it, and it is not adapted for domestic purposes when used alone, for the reason that when used under ordinary conditions and without special treatment it leaves a sediment which will discolor the 60 clothing.

When my improved bluing is sifted into water, either hot or cold, it is found to completely dissolve while it remains in suspension in the water. The dissolving action is 65 extremely rapid and no sediment is observable. This very desirable result is accomplished by the admixture of the bluing with the borax. The latter exerts an action that may be mechanical or chemical or both, 70 which induces a rapid dissolution of the particles of bluing so that a clear solution is obtained almost instantly. Hence no streaking or discoloration of the clothing is possible. Furthermore, all souring of the cloth- 75 ing is avoided. In practice the clothing may be permitted to soak for a number of days and yet it will be found clean and sweet when removed.

I prefer to adhere to the percentages 80 given, namely, 95 per cent. of borax and five per cent. of blue, since these proportions secure the most favorable results. They may, however, be varied from within the invention. 85

What I claim is:—

A laundry bluing comprising approximately 95 per cent. of finely powdered borax mixed with approximately five per cent. of soluble Prussian blue. 90

In witness whereof, I have hereunto signed my name in the presence of two subscribing witnesses.

ADRIANNA STÜRCKE.
